UNITED STATES PATENT OFFICE.

MAXIMILIAN F. BONZANO, OF NEW YORK, N. Y.

RAIL-FASTENING.

No. 922,843.

Specification of Letters Patent.

Patented May 26, 1909.

Application filed January 5, 1909. Serial No. 470,781.

To all whom it may concern:

Be it known that I, MAXIMILIAN F. BONZANO, a citizen of the United States, residing in the city and county of New York, State of New York, have invented a new and useful Rail-Fastening, of which the following is a specification.

In a prior patent No. 908,860, granted to me December 15, 1908, for a rail fastening, I have described and broadly claimed a novel construction of a rail fastening that is positive in its action, incapable of movement when once set in place, but capable of adjustment when necessity requires the setting over of the rail to restore the original gage of the track when the rails become worn or to change the gage of the track and in my present invention I have devised a novel construction of a rail fastening which may be considered as an improvement and further development of such patent.

To the above ends my present invention consists of a novel construction of a rail fastening which is especially adapted to be employed in cases wherein the rail chair is embedded or partially embedded in concrete as is the case under present methods of constructing a large number of traffic railway systems, such as subway lines and street traffic systems.

My invention further consists of a novel construction of a rail fastening, by the employment of which the rail is securely held in its proper position and wherein the gage of the rail may be readily and quickly adjusted without removing the chair from its concrete or other embedment.

It further consists of a novel construction of a chair wherein the rails may be laterally adjusted when desired and the fastening devices removed, inserted or adjusted without removing the chair from its bed.

It further consists of a novel construction of clips, a novel construction of wedges co-acting with said clips and with shoulders or flanges on the chair, and novel means for preventing improper movement of the fastening devices after they have once been adjusted.

My invention further consists of other novel features of construction, all as will be hereinafter fully set forth.

For the purpose of illustrating my invention, I have shown in the accompanying drawings, certain forms thereof, since these embodiments will give in practice, satis-

factory and reliable results, although it is to be understood that the various instrumentalities of which my invention consists can be variously arranged and organized and that my invention is not limited to the precise arrangement and organization of these instrumentalities as herein set forth.

Figure 1 represents a perspective view of a rail fastening embodying my invention, the same being shown in assembled position with respect to the rail. Fig. 2 represents a perspective view of one of the clips employed. Fig. 3 represents a transverse section of Fig. 1. Fig. 4 represents a top plan view of the chair in detached position. Fig. 5 represents a top plan view of Fig. 1. Figs. 6, 7 and 8 represent top plan view of other embodiments of my invention. Fig. 9 represents a section on line x-x, Fig. 8.

Similar numerals of reference indicate corresponding parts in the figures.

Referring to the drawings:—1 designates my novel construction of chair, the same comprising the top table 2 provided at opposite ends with the depending ends or standards 3.

4 designates a shoulder on each side of the chair 1, the inner face of said shoulder being preferably inclined as indicated at 5, at an angle to the top surface of the table 2.

6 designates an elongated slot through the table 2, said slot being provided intermediate its end with a polygonal shaped aperture 7 which in the present instance I have shown as being substantially square, whereby the same is adapted to receive the head of the bolt 8 or equivalent fastening device employed.

9 designates a clip having an aperture therethrough, through which the fastening devices 8 are adapted to pass, said clip being provided with the laterally extending flanges 11 and 12 and one side of the clip is provided with serrations or teeth 13.

14 designates wedges adapted to be seated on the table 2, said wedges having their outer edge shaped as at 15 to engage the inner faces of the shoulder 4. The inner faces of the wedges 14 are provided with serrations or teeth 16. These serrations may be in a plane angularly inclined to the outer face of the wedges 14, thereby adapting the teeth on the wedges 14 to interlock with the teeth of the clips 9, as will be readily apparent from Fig. 1; in which figure the parts are shown in their assembled position.

17 designates a rail of any usual or conventional type having its base flange securely held in position by the clips 9 and their adjuncts, it being noted that the clips 9 are 5 preferably provided with a fillet 18 whereby the clips 9 are adapted to closely engage with the edge of the base flange, while the flange 12 engages the top of the rail flange.

19 designates a nut having threaded or 10 other engagement with the fastening device 8: In order to prevent improper movement of the nut, I employ a lock washer 20 provided with an upwardly extending flange 21 which is adapted to engage a side of the nut 15 and prevent the improper rotation thereof, it being noted that in this embodiment the lock washer 20 is provided with three extensions or fingers 22, 23 and 24, the ends of which are deflected downwardly in order to 20 engage with the sides of the clip 9 and thereby prevent any improper movement of the lock washer 20 or the nut 19 after it has once been adjusted in position, it being understood that the ends of the extensions 22, 23 25 and 24 may be deflected downwardly before or after the nut 19 has been adjusted.

It will be understood by reference to Fig. 3 that I employ two sets of wedges, clips and fastening devices on opposite sides of the rail 30 and when it is desired to locate the fastening device in the track the chair 1 is placed in the desired location and suitably embedded or secured to the road bed. The heads of the fastening bolts 8 are passed through the aperture 7 so that such bolts may be moved in 35 the slot 6 to opposite sides of the aperture 7. The rail 17 is now placed in position with its flange resting on the table 2. The wedges 14 are placed on the table 2 so that the inclined 40 faces 15 engage with the inclined faces 5 of the shoulders 4. The clips 9 are then placed in position with the bolts 8 passing therethrough and the teeth 13 intermesh with the teeth 16 of the wedges 14 and the flange 12 45 extends over the flange of the rail 17 so that the parts are rigidly maintained in their assembled position. The lock washer 21 and nuts 19 are then secured in place so that any 50 improper movement of the parts after being adjusted, is prevented. Since the clips 9, wedges 14, lock washers 20 and cap nuts 19 employed are all constructed in substantially the same manner, I have given these elements the same reference characters in all the views.

55 In the embodiment seen in Fig. 6 I have shown a construction wherein a chair 25 is employed, of a construction somewhat similar to the construction seen in Figs. 1 to 5, inclusive, except that the shoulders 26 thereof 60 are provided with an inner face 27 angularly inclined to the top table of the chair but instead of having this shoulder 26 extending parallel with the rail 17, it extends at an angle thereto. The wedges 28 have their 65 outer faces adapted to coact with the inner

face 27 of the shoulder 26 while their inner face is provided with teeth 29 which are in a plane parallel with the rail 17. Instead of employing in this embodiment a slot 6 extending beneath the rail, I employ an elongated slot 30 in each clip and a round hole in the table of the chair through which the fastening device 32 extends, which is provided with a suitable nut 33. The clip 34 has its teeth 35 which intermesh with the teeth 29 located parallel with the rail 17. The lock washer 36 is provided with an upwardly deflected portion 37 which co-acts with a side of the nut 33 to prevent its improper movement, said clip having also the deflected ends 38 and 39 which engage opposite sides of the clip and thereby prevent any improper movement of the nut 33.

In the embodiment seen in Fig. 7 the chair 40 is shown as being of less width than the 85 clips 42 and the clips 42 are provided with depending flanges 43 which engage opposite sides of the chair, as will be understood by reference to Fig. 9. The shoulders in this embodiment are parallel with the rail while 90 the teeth on the inner face of the wedges 41 and on the outer face of the clips 42 are angularly inclined with respect to the longitudinal axis of the rail 17. A locking washer 44 in this embodiment is shown as 95 having one end deflected downwardly as indicated at 45, in order to prevent any improper movement of the nut 47.

In the embodiment seen in Fig. 8 I have shown the chair 40 as having its shoulders 48 100 extending at an angle to the longitudinal axis of the rail 17, while the inner serrated face of the wedge 49 is shown as being parallel with the longitudinal axis of the rail so that such serrations are adapted to intermesh with the teeth 50 on the clip 42, said teeth 50 extending parallel to the longitudinal axis of the rail 17. The lock washer 51 in this embodiment is shown as being constructed in a similar manner to that seen in 110 Figs. 1, 3 and 5. In this embodiment the chair is provided with separate elongated slots 31 for each bolt.

It will be apparent that while in the present instance I have shown elongated 115 slots through which the fastening devices pass as being located in the chair and a single aperture through the clips, that this may be reversed if desired, and the elongated slot may be located in the clip instead of in 120 the chair or in both the chair and clip at the same time and the adjustment may be accomplished in a similar manner to that hereinbefore described. The depending flanges 43 seen in Figs. 7, 8 and 9 aid in 125 preventing the shear on the bolts while at the same time the horizontal adjustment of the clips 42 is permitted.

It will be apparent that in all the embodiments of my invention, I have shown a 130

5 rail fastening wherein the rail may be readily and quickly adjusted or replaced, or set to line and gage without removing the chair from its place in the road bed and when it is desired to replace the fastening devices this may be readily and quickly accomplished.

10 In the majority of cases the chair would be embedded in the sub-structure of the road bed but in some cases the chair would be secured to a wooden, metal or other tie of any suitable or conventional type and it is to be understood that such use of my novel construction is within the scope of 15 the invention.

It will now be apparent that I have devised a novel and useful construction of a rail fastening which embodies the features of advantage enumerated as desirable in 20 the foregoing and while I have in the present instance shown and described certain embodiments thereof which will give in practice satisfactory and reliable results, it is to be understood that they are susceptible of 25 modification in various particulars, without departing from the spirit or scope of the invention or sacrificing any of its advantages.

Having thus described my invention what I claim as new and desire to secure by Letters Patent, is:—

1. As a new article of manufacture, a rail support consisting of a chair having a top table upon which the rail rests and provided with one or more slots for the rail fastening 35 devices, said slots extending at substantially right angles to the rail having shoulders co-acting with the fastening devices to permit lateral adjustment of the rail, and said table having depending standards connected therewith.

2. In a rail fastening, a chair having an oblong opening in its rail supporting surface extending at substantially right angles to the rail, flanges on said chair, said chair having depending standards thereon means engaging said opening for securing a rail to the chair, and devices co-acting with said flanges and said means for effecting the lateral adjustment of the rail.

3. In a rail fastening, a chair having a slot in its rail supporting surface and extending at substantially right angles to the axis of the rail, flanges on said chair, said chair having depending standards thereon means in said slot for securing a rail to the chair, and devices co-acting with said flanges and said means for effecting the lateral adjustment of the rail.

4. In a rail fastening, a chair having a slot in its rail supporting surface at substantially right angles to the rail, flanges on said chair, said chair having depending standards thereon means laterally adjustable in said slot for securing a rail to the chair, and devices co-acting with said flanges and

said means for effecting the lateral adjustment of the rail, said devices and means having interlocking means common thereto.

5. In a rail fastening, a chair, having an elongated slot in its rail supporting surface and extending at substantially right angles to the rail, flanges on said chair, said chair having depending standards thereon means in said slot for securing a rail to said chair, and wedges having a serrated edge interlocking with said means, said wedges co-acting with said flanges and means to effect the lateral adjustment of the rail.

6. In a rail fastening, a chair having a slot in its rail supporting surface at substantially right angles to the rail, flanges on said chair, said chair having depending standards thereon fastening devices located in said slot for securing a rail to the chair, said slot having a portion thereof shaped to permit insertion of said fastening devices, said fastening devices including laterally adjustable clips, and means co-acting with said flanges and clips for effecting the lateral adjustment of the rail.

7. In a rail fastening, a chair adapted to be embedded in the sub-structure of the road bed and having a top table provided with a slot in its rail supporting surface at substantially right angles to the rail, clips carried by said table and having a flange overlying the rail flange, fastening devices engaging said seat and said clips for securing the rail in its adjusted position, flanges on said chair, said chair having depending standards thereon and means co-acting with said flanges and said clips and interlocking with the latter to laterally adjust the rail.

8. The combination in a rail fastening, of a chair having depending standards adapted to be embedded and having a slot in its rail supporting surface extending at substantially right angles to the rail, fastening devices laterally adjustable in said slot, said devices including clips movably carried by the chair for securing a rail thereto, and adjusting means co-acting with said clips and disposed in engagement with the flanges of the chair.

9. The combination in a rail fastening, of a chair having a slot in its rail supporting surface extending at substantially right angles to the rail, clips movable on said chair, fastening devices engaging said slot and clips for securing a rail in adjusted position, flanges on said chair, said chair having depending standards, and adjusting blocks interposed between said clips and said flanges, said clips and adjusting blocks being adapted to interlock and said clips having a flange overlying the adjusting blocks.

10. The combination in a rail fastening, of a chair adapted to be embedded in the road bed and having a slot in its rail sup-

porting surface extending at substantially right angles to the rail, clips carried by said chair and having a flange overhanging the rail flange, fastening devices laterally adjustable in said slot for securing said clips in adjusted position, flanges on said chair, said chair having depending standards connected therewith, and wedges disposed between said flanges and said clips and having flanges 10 overlying said wedges.

11. The combination in a rail fastening, of a chair having a table provided with flanges on opposite sides thereof, said table having a slot therein extending at substantially right angles to the rail, said table having a standard extending downwardly therefrom clips laterally adjustable on said table for engaging a rail flange, bolts adjustable in said slots and passing through said clips, 15 nuts for said bolts, means for locking said nuts, and adjusting means disposed between said flanges and said clips.

12. In a rail fastening, a chair with flanges and having depending standards adapted to be embedded and having a slot inclined at substantially right angles to the axis of the rail, said slot having an enlargement to permit insertion of the fastening devices, clips carried by said chair through which said 20 fastening devices pass, wedges on said chair adapted to interlock with said clips and disposed intermediate said clips and said flanges, and said clips having flanges overhanging the rail flange.

13. In a rail fastening, a chair having separate slots therein, said chair having a standard extending downwardly therefrom flanges on said chair, clips laterally movable on said chair and having flanges overlying the rail flange, adjusting blocks intermediate said 25

flanges and said clips and adapted to interlock with the latter, the inner faces of said adjusting blocks and the outer faces of said clips being angularly inclined to the axis of the rail, and means for securing said clips 45 in adjusted position.

14. In a rail fastening, a chair having separate slots therein, flanges on said chair, clips laterally movable on said chair and having flanges overlying the rail flange, adjusting 50 blocks intermediate said flanges and said clips and adapted to interlock with the latter, the inner faces of said adjusting blocks and the outer faces of said clips being angularly inclined to the axis of the rail, and 55 means for securing said clips in adjusted position, the width of said chair being less than the width of said clips or wedges.

15. In a rail fastening, a chair having slots therein extending at substantially right 60 angles to the rail, flanges on said chair, clips carried by said chair and having depending flanges engaging the sides of said chair, said clips engaging the rail flange, devices disposed between said chair flanges and said 65 clips for laterally adjusting the rail, and fastening means for said clips.

16. In a rail fastening, a chair, flanges on said chair, clips having slots therein and engaging a rail flange, fastening devices for 70 said clips, and adjusting means disposed between said clips and said flanges, the inner face of said adjusting means being arranged parallel with the rail flange and adapted to interlock with said clips.
